ATTORNEY

UNITED STATES PATENT OFFICE.

ROBERT S. BURCH, OF CARMONA, TEXAS.

CHIMNEY-COWL.

1,258,865.

Specification of Letters Patent. Patented Mar. 12, 1918.

Application filed March 16, 1916. Serial No. 34,688.

To all whom it may concern:

Be it known that I, ROBERT S. BURCH, a citizen of the United States, residing at Carmona, in the county of Polk and State 5 of Texas, have invented certain new and useful Improvements in Chimney-Cowls, of which the following is a specification.

The present invention has relation to certain new and useful improvements in chimney cowls and as its primary object it contemplates the provision of a novel device of this nature that is of a construction whereby it may be easily and quickly associated with the respective chimney or smoke stack and 15 which, when in place will insure a proper draft at all times and collect the sparks so as to prevent the same from falling on and igniting the roof or other combustible object.

20 A further object of my invention is to provide a device of the type in question that is extremely simple in construction, strong and durable, and highly practical from both the standpoint of the manufacturer and the 25 standpoint of the user; and which, it is believed, may be manufactured at a comparatively low cost.

These objects are accomplished by such means as are shown in their preferred form 30 in the accompanying drawings, described in the following specification and then more specifically pointed out in the appended claims.

In the accompanying drawings wherein 35 like characters designate like parts throughout the several views:

Figure 1 is a view in vertical section of my invention showing the same as applied to the top section of an ordinary stove pipe 40 or smoke stack.

Fig. 2 is a view in cross section taken on line 2—2 of Fig. 1.

Fig. 3 is a view similar to Fig. 1 taken at a different angle.

45 In reducing my invention to practice, I first provide a body or clamping member 10 that is designed to fit about the upper end of the stove pipe or smoke stack as the case may be, the same being preferably constructed of sheet metal and in a manner whereby its diameter may be readily adjusted in order to compensate for the various diameters of the smoke stacks. At 50 certain points about its circumference, the body member 10 is provided with a series

of upstanding supporting arms 11, as at 12, the said supporting arms in turn carrying a hood or bonnet 13 which when the device is in place is substantially coaxially aligned with the stove pipe or smoke stack such as 60 indicated by the letter A.

As will be noted upon reference to Fig. 3, the bonnet or hood 13 is substantially hemi-spherical thereby affording an adequate protection for the pipe or stack and preventing the entrance of rain or other extraneous matter. This bonnet or hood may be constructed of any desired material, however it is pointed out that a light metal is 70 preferable.

A suitable curved support or yoke 14 is mounted to be revoluble with respect to the hood or bonnet 13 through the instrumentality of a stud 15, one end thereof projecting below the lower edge of the hood or 75 bonnet and designed to carry a semi-cylindrical guard plate 16, secured thereto by means such as shown at 17. This guard plate is to be of a width substantially the same as the distance between the upper edge of the 80 body member 10 and the lower edge of the hood or bonnet whereby it will afford an adequate shield which, as is obvious, is readily movable to different positions about the vertical center of device. The other 85 end of the yoke 14 is extended downwardly, as shown in Fig. 1, to form a back or securing portion 18 and an angularly extending supporting portion 19. A substantially semi-circular basket 20 that may be formed 90 of any recticular or interstitial material may now be associated with the arm 14 in the manner shown in Fig. 1, a portion thereof being connected to the portion 18 of the yoke as shown at 21 while the portion 19 95 of the yoke extends beneath the basket and may be connected thereto as at 22. Consequently it will be recognized that the basket will be held securely in position at all times, while the portion 19 of the yoke forms an 100 adequate support for the bottom of the basket to relieve the strain thereon when foreign material has accumulated therein.

As is obvious upon reference to Fig. 2, the basket 20 is diametrically opposed to the 105 guard plate 16 and movable together therewith, whereby the smoke passing upwardly from the stack or pipe A will pass outwardly through the basket in the usual manner, while the guard plate is of course shifted at 110

certain times, as will hereinafter appear, in accordance with the variation of the air current.

I further provide a vane 23 that may be fixed to the yoke 14 through the instrumentality of a member 24 and fastening members 25 thus providing for the proper adjustment of the guard plate 16 and the basket in accordance with the variation of 10 the air current, as stated above.

The supporting members 11, being placed on the inner periphery of the body member 10, and the bonnet 13 do not in any way 15 impede movement of either the guard plate 16 or the basket 20, thereby insuring efficient operation of the device at all times.

The operation of my invention is substantially as follows:—

The device may be quickly arranged in 20 connection with the stove pipe or chimney, such as above set forth, whereby it will be in a position for immediate operation. The air current, acting on the vane 23, will of course shift the vane to various positions 25 which will in turn cause the actuation of the guard plate 16 and the basket 20 as above referred to. The smoke passing through the basket 20 will be relieved of sparks and other foreign matter, the latter falling onto the bottom of the basket. Both 30 the guard plate 16 and the basket 20 are readily rotatable with respect to the chimney by reason of the efficient support of the carrying arm 14 and by reason of this construction it will be noted that the device is 35 not likely to get out of order.

From the foregoing it is believed that the 40 advantages and novel features of my invention will be readily understood and therefore further detail description is deemed unnecessary.

In reducing my invention to practice I 45 find that the form referred to herein as the most practical and preferred embodiment is the most efficient, but realizing that certain conditions will necessarily vary in concurrence with the adoption of my device, I desire to emphasize the fact that various minor changes in the details of construction and in the proportion of parts may be resorted to 50 when required without sacrificing any of the advantages of my invention as defined in the appended claims.

Having thus fully described my invention, 55 what I claim as new and desire to secure by Letters Patent, is:—

1. A chimney cowl comprising a hollow body, an impervious hood extending over the hollow of said body and being spaced thereabove, and supported by said body, a support pivotally mounted on said hood and extending from side to side of the latter, a wind shield supported by one end of 60 said support and substantially closing one side of the space between said body and

hood, a reticular element supported by the other end of said support and disposed diametrically opposite to said wind shield and covering a portion of the space between said body and said hood, and means operable by the wind for turning said support on its pivot. 70

2. In a chimney cowl, supporting means associated with the chimney or stack, arms carried thereby, a hood carried by said arms, a carrying member rotatably mounted on said hood, a guard plate carried by said carrying member and interposed between said hood and the upper edge of the chimney or stack, a basket of reticulated material 80 carried by said carrying member diametrically opposite to said guard plate, through which the smoke passes, and a vane to be associated with said carrying member, whereby the guard plate and said basket 85 may be moved in consistence with the variation of the air current, as and for the purpose specified. 75

3. A chimney cowl consisting of a hollow body attachable to a chimney, a hood 90 extending over said hollow body, a plurality of arms each having one end within said hollow body and secured thereto and have its other end within said hood and secured thereto so as to support the hood in spaced 95 relation above said hollow body, a yoke pivotally mounted on said hood, a windshield carried by one end of said yoke, and substantially covering one side of the aperture between said hollow body and hood, a reticular 100 spark-arresting element separated by the other end of said yoke and substantially covering the opposite side of said space, and a vane carried by said yoke and operable by the wind for rotating the yoke and windshield and reticular element exteriorly of 105 the said arms. 100

4. In a chimney cowl, a body member adapted to be associated with the chimney or stack, a bonnet arranged above said body 110 member in spaced relation, means carried by said body member to support said bonnet, a carrying arm revolvably mounted with respect to said bonnet, and supported thereby, a guard member carried by one end of 115 said arm and interposed between said bonnet and said body member and movable with respect to said body member and said bonnet, a basket formed of reticulated material and carried by the other end of said arm 120 and arranged oppositely with respect to said guard plate, means carried by said arm to support the bottom of said basket, and a vane associated with said carrying arm, whereby said guard and said basket may be 125 moved in consistence with the variation of the air current, as and for the purpose specified. 125

5. In a chimney cowl, a body member to be associated with the chimney or stack, a 130

substantially hemi-spherical bonnet, means carried by said body member to support said bonnet in co-axial alinement therewith, a yoke revolubly mounted on said bonnet, a
5 guard plate carried at one end of said arm and interposed between said body member and said bonnet, a basket formed of reticulated material and carried by the other end of said yoke and arranged opposite to said
10 guard plate, means carried by said arm to extend under and support the bottom of said basket, said basket being arranged in the manner whereby the smoke will pass therethrough, and a vane associated with said carrying arm, whereby said guard plate and said basket may be moved consistent with the variation of the air current, as and for the purpose specified. ¹⁵

In testimony whereof I affix my signature in presence of two witnesses.

ROBERT S. BURCH.
